ATTORNEY'S.

UNITED STATES PATENT OFFICE.

CHARLES A. LEE, OF CANASTOTA, NEW YORK.

FOOT-REST.

SPECIFICATION forming part of Letters Patent No. 590,268, dated September 21, 1897.

Application filed September 8, 1896. Serial No. 605,081. (No model.)

To all whom it may concern:

Be it known that I, CHARLES A. LEE, of Canastota, in the county of Madison and State of New York, have invented certain new and useful Improvements in Foot-Rests; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to improvements in adjustable foot-rests for chairs.

In the drawings, Figure 1 shows a perspective view of my improved foot-rest. Fig. 2 shows a section of the same in extended position. Fig. 3 shows the same in folded position. Fig. 4 shows details of a hook-like catch employed in the construction of the frame. Fig. 5 shows details of a double hook employed on the adjustable arms of the device.

The frame of the device consists of a pair of bars 1 1, connected by cross-bars 2 3 and provided with supporting-legs 4 on the outer end.

It will be understood that the inner end of the frame is supported on the base of a chair, and the arms 1 1 are adapted to slide under or draw out from the base of the chair.

In the construction shown in Figs. 1 to 5, inclusive, the frame is provided with a cross-rod 5, on either end of which are mounted the slotted arms 6 6, the rod passing through the slots of the arms. These arms are connected at their upper end by a spindle or bar 7 and carry at their upper or swinging ends the stool-top 8, which is hinged thereto at 9. On the cross-bar 2, at either end and opposite the arms 6 6, are secured hooks 10. These hooks 10 are adapted to be engaged by either of the hooks 11 11 on the back side of the arms 6. These two hooks 11 are preferably mounted on a common base, as shown in Fig. 5.

By the employment of the two hooks 11 11 the stool-top may be given two elevations with

respect to the frame, the lower one of which is shown in Fig. 1 and the higher one in Fig. 2. Of course it will be understood that hooks 11 can be employed to give several variations in adjustment; but I deem two sufficient.

The relative size of the rod 5 and the slot x in the arm 6 is such that no side play is permitted, and when the hooks 11 are engaged with the hooks 10 the arms are firmly secured. There is, however, provided at the extreme lower end of the slots x in the arm 6 an enlargement x' on the side, which when the arms 6 are folded into the frame, as shown in Fig. 3, receives the bar 5 and forms a sort of hook, preventing the stool-top, with its arms, from sliding backward and forward in the frame. The relative arrangement of the rod 5 and enlargement x' of the slot x is as shown in Fig. 2, so that when the lower hook 11 is engaged with the hook 10 the bar 5 will not be opposite the enlargement x' , but a little above it in the slot, whereby the arms are firmly held from the swinging movement while the hooks 11 are in engagement.

What I claim as new, and desire to secure by Letters Patent, is—

1. The combination in a foot-rest of the frame having bar 2 with hooks 10, 10 and rod 5, the slotted arms 6 running on the bar 5 and provided with hooks 11, 11 adapted to engage the hooks 10, 10 and the stool-top 8 hinged on the ends of the arms 6, substantially as set forth.

2. The combination in a foot-rest of a frame having a cross-bar 2 with hooks 10, 10 and cross-rod 5 located with reference to bar 2 as shown, arms 6 having slot x and enlargement x' arranged as described, mounted on the cross-rod and provided with hooks 11, 11, and the stool-top hinged to the upper end of the arms.

In witness whereof I have affixed my signature in presence of two witnesses.

CHAS. A. LEE.
